(57) **CLAIM**

We claim the ornamental design for a front panel for an electric hunting vehicle, as shown.

DESCRIPTION

FIG. 1 is a front elevation view of a front panel for an electric hunting vehicle showing the new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a perspective view thereof.
